[57] CLAIM

The ornamental design for an adjustable step exerciser, as shown and described.

DESCRIPTION

FIG. 1 is a side elevational view of an adjustable step exerciser showing my new design, the side opposite being substantially a mirror image;

FIG. 2 is a top plan view thereof;

FIG. 3 is an end elevational view thereof, the end opposite being substantially a mirror image; and

FIG. 4 is a bottom plan view thereof.

*Fig. 2.**Fig. 1.**Fig. 3.**Fig. 4.*
